UNITED STATES PATENT OFFICE

2,644,456

LOOSE-LEAF BINDER

Allan O. Marsh, Los Angeles, Calif.

Application April 7, 1950, Serial No. 154,709

1 Claim. (Cl. 129—9)

1

The present invention relates to catalogue and loose leaf record filing apparatus and in particular to releasably attachable and detachable file sections whereby sections of a file held by the apparatus may be replaced and withdrawn. The present application forms a continuation in part of my earlier filed application, Serial No. 693,230, filed August 27, 1946, now abandoned for a Visible Display File.

In apparatus of this type arranged to maintain pages in separate attachable and detachable sections, it is desirable that such sections, after they are separated from the composite file, may be easily opened and closed for insertion or removal of pages into and from the composite file.

It is therefore an object of the present invention to provide improved releasably attachable and detachable file sections characterized by the ease and speed with which such sections may be disassembled to allow pages to be entered therein or removed therefrom.

Another object of the present invention is to provide an improved releasably attachable and detachable file section for holding a section of a complete file characterized by its ruggedness and minimum number of parts.

Still another object of the present invention is to provide an improved releasably attachable and detachable file section having integrally formed parts arranged to resiliently maintain the component parts together.

Yet another object of the present invention is to provide an improved releasably attachable and detachable file section, the two component parts of which may be fastened together by merely moving one part with respect to the other and which may be separated by either releasing a catch or by exerting a relatively large force between the members.

Yet a further object of the present invention is to provide an improved releasably attachable and detachable file section, the component parts of which may be inexpensively manufactured by using mass production methods such as by a stamping operation.

The features of the present invention which are believed to be novel are set forth with particularity in the appended claim. This invention itself, both as to its organization and manner of operation, together with further objects and advantages thereof, may be best understood by reference to the following description taken in connection with the accompanying drawings in which:

Figure 1 is a plan view of apparatus partly 55 ways are flared as indicated. Also some guided

2

fragmented incorporating the present invention, Figure 2 is a sectional view taken substantially on the line 2—2 of Figure 1, and

Figures 3 and 4, respectively, are sectional views taken substantially on the lines 3—3 and 4—4 of Figure 2.

The file structures having the general reference numeral 10 and each comprising only two L-shaped members 11, 12, are releasably attachable and detachable to the base supporting member 13.

The base supporting member 13 has a pair of longitudinally extending serrated or grooved bracket members 14 arranged to engage and maintain the file members 10 in position by cooperation with their integrally formed correspondingly serrated or grooved tongue members 15.

The base supporting member 13 is preferably formed from one or more sheets of metal and may be formed to present an inclined surface and adapted to rest on a flat table, desk or the like, as shown in my above mentioned application, or preferably, as shown herein the base supporting member may comprise either one plate or a plurality of flat backing plates or sheets welded together as indicated at 13A and of such size for convenient placement in a conventionally sized brief case and the like.

One of the important features of the present invention resides in the structure of the file structures 10. The file structure 10 comprises two L-shaped members, a so-called inner member 11 and an outer member 12.

The vertical portions of such L-shaped members 11 and 12 have affixed thereon, respectively, paper holding pins 25 and 26 arranged to enter apertured portions 27 and 28 in opposite vertical positions. When the pins 25 and 26 are moved into position in their corresponding apertures 27 and 28, the two L-shaped members 11 and 12 are automatically locked, one with respect to the other, due to cooperation of the resilient tongue members 28a and 29 carrying the integrally formed raised portions 30 and 31, respectively, with the apertured portions 32 and 33 in member 12.

In such relative movement of members 11 and 12 to produce locking thereof, member 11 is guided with respect to member 12 in the passageways 32a and 33a formed by turning back the end portions 34 and 35, respectively, of member 12. One important feature of this construction is that the openings or mouths to such passageways are flared as indicated. Also some guided

movement for relative movement of members 11 and 12 is provided by the raised portions 30 and 31 of member 11 cooperating with the indented portions 36 and 37 and also by engagement of the tongue member 38 on member 12 with the apertured portion 39. All of these cooperating parts have been found very desirable in effecting movement of one file part 11 with respect to the other part 12 in assembling these parts to form the file 10.

Guided movement of member 11 with respect to member 12 results until there is engagement between the apertured portion 39 with the tongue member 38 which serves as a stop member. In the meantime, due to the resilient nature of the tongue members 28^a and 29, the raised portions 30 and 31 thereon engage the apertured portions 32 and 33 to thereby lock members 11 and 12 together. These two members may be then unlocked by exerting a relatively large tension force between the members 11 and 12 to thereby cause the raised portions 30 and 31 to be cammed out of engagement with the apertured portions 32 and 33 or, preferably, a person by his thumb or finger presses down on the free end of the tongue members 28^a and 29 extending into the apertured portions 32 and 33 and simultaneously pulls the members 11 and 12 apart by applying a relatively small tension force therebetween.

Another important feature of the present invention is provision of the serrated or grooved bracket member pairs 14 or hooks which have a cross section as shown in Figure 2 and are affixed to the backing plate 13 as, for example, by welding 13B, in a position for cooperation with the serrated or grooved tongue members 15 as shown in Figure 4. It is observed that the cooperating grooved or serrated cooperating engaging faces on the members 14 and 15 is of such nature as to provide a relatively good anti-friction connection for vertical movement of the composite file 10 in Figure 1 with respect to the relatively stationary hook or bracket members 14, but yet prevents lateral or horizontal movement of the composite file with respect to such relatively stationary bracket or hook members 14.

Another important feature of the present invention is the provision of the file locking arrangement 50 mounted along the upper edge of the backing plate 13. This locking arrangement 50 includes a longitudinally extending treadle bar 51 of sheet metal which is retained on the backing plate by the pair of posts 52, 53 in the form of rivets which are affixed to the backing plate 13 and extend through enlarged holes in the treadle bar 51 with enlarged heads on such posts 52, 53 retaining the bar in position. These posts 52, 53 in the form of rivets further serve to anchor one end of a leaf spring 56 having its free end pressured into engagement with the lower portion 51B of the treadle bar to normally press the same outwardly in a position where the free end, as shown in Figure 2, blocks upward movement of the composite file 10, if an attempt is made, accidentally, inadvertently or otherwise to pull the engaged members 14, 15 out of engagement. In such locking position the upper portion 51B of the treadle bar 51 engages the backing plate 13 to limit movement which otherwise would be produced by the leaf spring 56.

While the treadle bar 51 is shown as one piece to extend the full width of the backing plate 13, it is within the province of the present invention to sectionalize such treadle bar 51 so that there is a single treadle bar for each one of the file structures 10. Each one of such sectionalized treadle bars may carry suitable indicia to indicate the indexed position of the corresponding file structure 10.

10 When it is desired to remove the composite file structure 10 from its assembled position on the backing plate 13, as shown in Figure 2, it is first necessary to press the treadle bar 51 inwardly (to the right in Figure 2) against the action of spring 56 to move the treadle bar end 51A out of the blocking position. Thereafter, the file structure 10 is raised upwardly with respect to the backing plate 13 to "break" the resilient connection existing between the cooperating serrated or grooved contacting surfaces of tongue 15 and bracket or hook 14.

While the particular embodiments of the present invention have been shown and described, it will be obvious to those skilled in the art that changes and modifications may be made without departing from this invention in its broader aspects and, therefore, the aim in the appended claim is to cover all such changes and modifications as fall within the true spirit and scope of this invention.

I claim:

A file structure having only two parts for binding the pages of a file, each of said parts being L-shaped and each having at least one page holding pin extending in the direction of the vertical leg of the other L-shaped part, cooperating guide means formed integrally with the horizontal legs of said L-shaped parts, a resilient tongue member having a detent formed on one of said horizontal legs arranged to maintain the other one of said horizontal legs in locked position, said cooperating guide means comprising a pair of passageways at opposite ends of one of said parts with flared mouths thereto adapted to receive the horizontal leg of the other part, said tongue member cooperating with a notched portion which is disposed at the junction of the horizontal and vertical legs of the corresponding part, and said corresponding part having an indented portion adjacent said notched portion to serve as a guide for movement of said resilient tongue member into said notched portion.

ALLAN O. MARSH.
